(57) **CLAIM**

The ornamental design for a display screen as shown and described.

DESCRIPTION

1. Display screen
- 1.1 : Front perspective
- 1.2 : Rear perspective
- 1.3 : Front
- 1.4 : Rear
- 1.5 : Left
- 1.6 : Right
- 1.7 : Top
- 1.8 : Bottom
- 1.9 : Reference
- 1.10 : Reference
- 1.11 : Reference

Reproduction 1.9 is a reference view, showing the display screen of reproductions 1.1-1.8 in a state of use in which the rear stand is unfolded. Reproductions 1.10 and 1.11 are reference views, showing the display screen of reproductions 1.1-1.9 in alternate configurations of use with environment. The broken lines, showing a support attached to the rear surface of the display screen in reproductions 1.10-1.11, illustrate environmental structure and form no part of the

(Continued)

claimed design. All remaining broken lines illustrate portions of the display screen that form no part of the claimed design. The portion of the design shown in the color gray is for the purpose of illustrating portions of the display screen and forms no part of the claimed design.
